UNITED STATES PATENT OFFICE.

EDWARD L. MORRIS, OF BOSTON, MASSACHUSETTS.

DESIGN FOR A TOY FULMINATE-EXPLoder.

SPECIFICATION forming part of Design No. 13,063, dated July 18, 1882.

Application filed April 15, 1882. Term of patent 7 years.

To all whom it may concern:

Be it known that I, EDWARD L. MORRIS, a citizen of the United States, residing at Boston, in the county of Suffolk and State of Massachusetts, have invented and produced a new and original Design for Toy Fulminate-Exploders, of which the following is a specification, reference being had to the accompanying drawing, forming part thereof.

10 The design consists in the representation, as hereinafter shown and set forth.

In the accompanying drawing my design is illustrated. f is the handle of the toy, formed to represent a portion of a tree bent to about 15 the shape of a pistol or fire-arm. A represents the figure of a monkey, surmounting the handle f. m are arms pivoted to the body at b, and serving the purpose of a hammer. e is the tail, which is caused to serve the purpose of a 20 trigger. d is the receptacle for fulminate. c h e g i show the interior arrangement of the toy, which is similar to that of the ordinary toy pistol. When the tail e is pulled the arms m, holding the object k, descend upon the ful- 25 minute.

I claim—

1. The design for a toy fulminate-exploder, consisting of a hammer formed to represent the striking-arms m of the figure A, surmounting the handle f, substantially as shown and 30 described.

2. The design for a toy fulminate-exploder, consisting of a trigger formed to represent the tail e of the figure A, surmounting the handle f, substantially as shown and described. 35

3. The design for a toy fulminate-exploder, consisting of a handle surmounted by the figure of a monkey, a hammer formed to represent arms, and a trigger formed to represent a tail, substantially as shown and described. 40

4. The design for a toy fulminate-exploder, consisting of a handle formed to represent a portion of a tree, and surmounted by the figure of a monkey, substantially as shown and described.

EDWARD L. MORRIS.
